APPARATUS FOR TREATING COILED STRIP MATERIAL

George R. Beckwith, Brady Lake, and Clayton H. Propper, Kent, Ohio, assignors to The C. L. Gouger Machine Company, Kent, Ohio, a corporation of Ohio

Application June 20, 1936, Serial No. 86,388

6 Claims. (Cl. 242—73)

This invention relates to the treatment of strip material, and more particularly to a novel apparatus for preparing coiled strip material for subsequent treatment.

5 In certain manufacturing establishments, such as steel mills, material is produced in the form of strips of considerable length. As the strips are produced they are wound roughly onto reels or collapsible mandrels. These strips usually 10 require further treatment, such as pickling or annealing, and the present invention has to do with the preparation of such coiled strips for such subsequent treatment. As will be explained more fully hereinafter, the roughly coiled strip 15 is placed on a platform or table of a machine known as a "hype" machine and is subjected to winding and unwinding operations known as "hyping," whereby the adjacent convolutions of the coil are spread apart a desired distance.

20 It may, therefore, be regarded as an object of our invention to provide novel apparatus for treating coiled strip material to thereby space the adjacent convolutions from each other and thus prepare the coil for subsequent treatment.

25 Another object of our invention is to provide an improved machine, of the type mentioned, having a support adapted to receive a coil of strip material and a rotatable drive spindle adjacent such support adapted to be connected 30 with the inner end of the strip for imparting winding and unwinding torque thereto.

Yet another object of our invention is to provide an improved machine, of the type referred to, wherein the support for the coil comprises a 35 platform which is tiltable from one position to another.

The invention may be further briefly summarized as consisting in certain combinations and arrangements of parts hereinafter described 40 and particularly set out in the appended claims.

In the accompanying sheets of drawings:

Fig. 1 is a side elevation of a hype machine embodying our invention.

Fig. 2 is a top plan view thereof, but with certain portions broken away.

Fig. 3 is an end view of the machine illustrating the extreme positions to which the tiltable work support is movable.

Fig. 4 is a perspective view of a device used 50 to connect the inner end of the coiled strip with the drive spindle.

In the accompanying drawings we have shown what we now regard to be a preferred form of our novel hype machine and detailed reference 55 will be made to this particular machine. It

should be understood, however, that our invention is not necessarily confined to this particular apparatus, but may be embodied in various other machines and apparatus of this character.

In Figs. 1, 2 and 3 of the drawings we have shown a form of our hyping apparatus which is very satisfactory for ordinary and relatively light duty in preparing coiled strips for subsequent treatment. This machine is provided with a suitable frame 10 and a work support 11, preferably though not necessarily, in the form of a tiltable platform or table mounted on the frame and adapted to receive the individual coils of strip material. The work support 11 may be constructed with angularly extending legs, as shown in Fig. 3, one of which legs forms the table-like part or platform 12 and the other of which forms the coil retaining flange 13. This work support may have a shaft 14 mounted in openings of the stiffening ribs 15 thereof and may be tiltably mounted on the frame 10 by providing the latter with spaced bearings 16 in which the shaft is adapted to oscillate.

As shown in Figs. 2 and 3 of the drawings the tiltable work support 11 is mounted on the frame 10, so that the side or edge which carries the angularly extending flange 13 projects outwardly beyond the corresponding side or edge of the frame. This relative arrangement between the work support and the frame permits the retaining flange 13 to be swung downwardly to a coil receiving position, as illustrated in Fig. 3, in which position the face 17 of the flange 13 is substantially flush with the surface of the floor 18. The platform 12 of the work support may be provided substantially centrally thereof with an opening 19 and the face 17 of the retaining flange 13 may be provided with an arcuate coil locating recess 20 at a point substantially laterally opposite such opening.

A drive spindle 22 is rotatably mounted on the frame 10 adjacent the work support 11 for applying winding and unwinding torque to the inner end of the coiled strip which is received on the work support. This drive spindle may be mounted in bearings 23 and 24, to extend substantially vertically in coaxial relation with the opening 19 of the platform 12. The upper end of the spindle may be hollow and provided with internal splines 25 for establishing a driving connection with the member to be driven thereby. For driving the spindle 22 we provide power means on the frame, preferably in the form of a variable speed electric motor 27, which may be connected with a countershaft 28 by a drive

chain 29 or the like. The countershaft 28 may be connected with the spindle 22 by means of a bevel gear 30 and a bevel pinion 31. A manually operable controller 32 may also be provided on the frame 10 for controlling the speed and direction of rotation of the spindle driving motor 27.

As indicated in the drawings, the work support 11 is movable to a position with the platform 12 extending substantially horizontally, in which position the upper end of the drive spindle 22 is accessible through the opening 19 for establishing a drive connection between the spindle and the inner end of the strip of the coil supported on the platform. As mentioned above, the work support is also movable about the axis of the shaft 14 to the broken line coil-receiving position illustrated in Fig. 3. For moving the work support from one of these positions to the other we provide a rock shaft 33 having a crank arm 34 which is connected with a lever portion 35 of the work support by means of a link 36. The shaft 33 is mounted on the frame in suitable bearings provided therefor and is driven from an electric motor 37 through a speed reducing device 38.

The tilting motor 37 may be controlled by suitable apparatus including a push button 39 and a magnetic switch device 40 for starting the motor. This control apparatus may also include a limit switch device 41 which is associated with the shaft 33 and is operable to stop the motor when the work support has been moved to one or the other of its extreme positions. The apparatus for controlling the motor 37 may also include a reversing device 42 to provide for movement of the work support in both directions.

In the operation of the apparatus just described, and in carrying out our novel method, the operator starts the motor 37 and thereby causes the work support 11 to be tilted to the broken line position shown in Fig. 3. While the work support is in this position a coil of strip material is placed in the recess 20 of the retaining flange 13 and with an end of the coil against the platform 12. The operator then reverses the motor 37 to tilt the work support to its full line position shown in Fig. 3, in which position the opening 19 of the support is brought into coaxial relation with the upper end of the drive spindle 22. The coil is then shifted on the platform 12, if this be necessary, to bring the central opening of the coil in substantial alignment with the drive spindle 22. The collapsible mandrel or reel upon which the coil was previously wound is removed from the central opening and a mandrel or core 44 of suitable form is inserted into the coil opening. A suitable form of such mandrel shown in Fig. 4 has a slot 45 or other connecting means thereon for engagement with the inner end of the strip and also has a splined shaft projection 46 adapted to engage in the splined opening of the spindle 22.

When the mandrel 44 has been thus inserted to establish a winding connection between the inner end of the strip and the spindle 22, the main motor 27 is started by the operator to rotate the spindle in a direction to apply winding torque to the inner end of the strip. The mandrel 44 which is inserted into the opening of the coil is of smaller diameter than the reel initially used in winding the coil, and the winding torque being applied to the inner end of the strip causes a substantially tight-winding of the strip onto the mandrel 44 thereby reducing the inner and outer

diameters of the coil. This winding of the coil to smaller inner and outer diameters causes relative movement between the adjacent convolutions of the coil, which results in the breaking of any adhesions between the convolutions, and also causes the forming of a coil of more regular shape.

Following this tight-winding of the coil to smaller diameters, the motor 27 is stopped and one or more of the outer convolutions of the coil are then manually backed off or expanded to substantially the outside diameter to which the coil is to be expanded. When this has been done the motor 27 is started but is operated in the opposite direction to cause the spindle 22 to apply unwinding torque to the inner end of the strip. This causes the convolutions of the coil to be expanded or unwound and thereby spaced apart. When sufficient unwinding torque has been applied to the strip to cause all of the convolutions to be thus spaced apart, the motor 27 is stopped and the expanded coil is now ready to be removed from the hype machine for delivery to the annealing, pickling or other subsequent treatment which it is to receive. After the coil has been thus expanded it may be tied at points to prevent shifting of the convolutions and may then be lifted from the platform by a magnet or other suitable apparatus for delivery to the station where it is to receive its subsequent treatment.

From the foregoing description and the accompanying drawings it will now be readily understood that we have provided novel apparatus for treating coiled strip material and thereby preparing the same for pickling, annealing or other subsequent treatment which the material is to receive. It will be understood furthermore that our novel method for treating the coiled material involves the novel steps of successively applying winding and unwinding torque to the inner end of the strip whereby the coil is first reduced to a tight-wound coil of smaller inner and outer diameters and is then expanded or unwound to move the convolutions outwardly into spaced relation to each other.

While we have disclosed the apparatus of our invention in a somewhat detailed manner it will be understood, of course, that we do not wish to be limited to the precise arrangements and details of construction herein disclosed, but regard our invention as including such changes and modifications as do not constitute a departure from the spirit of the invention and the scope of the appended claims.

Having thus described our invention, we claim:

1. In apparatus of the character described the combination of a frame, a rotatable spindle thereon, a support adapted to receive a coil of strip material, said support having an opening therein and being movable to position said opening substantially coaxially with respect to said spindle, means for driving said spindle, and means for connecting the inner end of said strip with the spindle.

2. In apparatus of the character described the combination of a frame, a rotatable spindle thereon, a support adapted to receive a coil of strip material, said support having a platform portion with an opening therein and being movable to position the platform opening substantially coaxially with respect to said spindle, a mandrel adapted to be inserted into the coil to connect the inner end of the strip with said

spindle, and power means on the frame for driving said spindle.

3. In apparatus of the character described the combination of a frame, a rotatable spindle thereon, a support adapted to receive a coil of strip material, said support having an opening therein and being movable to position said opening substantially coaxially with respect to said spindle, means for moving said support, means for connecting the inner end of said strip with said spindle, and means for driving the spindle.

4. In apparatus of the character described the combination of a frame having a rotatable drive member, a tiltable platform having an opening, means on the platform for retaining a coil of strip material thereon, means for tilting said platform to position said opening and coil with respect to the drive member, and means for establishing a winding connection between the inner end of the strip and said drive member.

5. In apparatus of the character described the combination of a frame, a tiltable work sup-

port thereon having angularly extending portions adapted to hold a coil of strip material, a rotatable spindle, one of said portions having an opening adapted to be brought into register with said spindle by tilting of the support, and means adapted to be inserted into the coil for connecting the inner end of the strip with said spindle. 5

6. In apparatus of the character described the combination of a frame, a rotatable spindle thereon, a variable speed motor having driving connection with said spindle, a tiltable work support having angularly extending portions adapted to hold a coil of strip material, one of said portions having an opening adapted to be brought into register with the spindle by tilting of the 10 support, means for connecting the inner end of the strip with said spindle, a motor driven shaft on said frame, and linkage connecting said shaft and support for causing tilting of the latter. 15
